UNITED STATES PATENT OFFICE.

JOSEPH K. DAVISON, OF PHILADELPHIA, PENNSYLVANIA.

DESIGN FOR A BADGE.

SPECIFICATION forming part of Design No. 23,279, dated May 22, 1894.

Application filed April 4, 1894. Serial No. 506,350. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for a Badge, of which the following is a specification, reference being had to the accompanying drawing, forming part thereof.

The leading feature of my design for a badge is a disk or plate with the representation of a knapsack thereon, and a camp kettle, a ridge pole and crotch sticks on said knapsack.

In the drawing: A designates a plate on the 15 face of which is the knapsack B.

C designates a camp kettle which is suspended from the ridge-pole D, the latter being supported on the crotch-sticks E, said kettle, pole and sticks being placed on the 20 knapsack.

What I claim is—

The design for a badge, substantially as shown and described.

JOSEPH K. DAVISON.
